ATTORNEY

UNITED STATES PATENT OFFICE.

ROBERT C. PRATT, OF CALHOUN, OKLAHOMA.

PROPELLER.

1,345,237.

Specification of Letters Patent. Patented June 29, 1920.

Application filed April 25, 1918. Serial No. 230,773.

To all whom it may concern:

Be it known that I, ROBERT C. PRATT, a citizen of the United States, residing at Calhoun, in the county of Le Flore and 5 State of Oklahoma, have invented certain new and useful Improvements in Propellers, of which the following is a specification.

This invention relates to propellers generally and particularly for application to 10 steam and other power driven ships and has for its object to provide a propeller which will be simple, strong and durable in construction, efficient in operation, and fully adapted to the purpose for which it is de- 15 signed.

A further object of the invention is to provide a thrust propeller which may be placed at the bow or stern of a vessel, or both at the bow and stern and connected to 20 suitable driving means which will impart a fore and aft movement thereto to cause swinging blades mounted in the propeller to act against the water when the propeller is moved rearwardly and provide a thrust 25 which will impel the vessel in a forward direction, the blades upon reverse movement of the propeller automatically folding to cause them to bear edge-wise against the water and so produce little resistance to said 30 reverse movement.

With these objects in view, together with others which will appear as the description proceeds, the invention resides in the novel formation, combination, and arrangement of 35 parts, all as will be described more fully hereinafter, particularly pointed out in the claims, and illustrated in the accompanying drawings, in which,—

Figure 1 is a side elevation of the im- 40 proved propeller in operative position upon a boat, one of the propellers being shown at the bow and another at the stern of the boat.

Fig. 2 is a perspective view of the propeller disengaged from the boat and shown 45 on a larger scale.

Fig. 3 is a vertical longitudinal sectional view of the propeller.

Fig. 4 is a similar view of the propeller showing a slight modification, and,

50 Fig. 5 is a longitudinal sectional view of a further modification showing a plural series of swinging blades.

In the drawings, 10 indicates a box-like frame of skeleton formation, said frame 55 being made of metal bars which shall be both strong and light and which also pre-

sent but little surface of the water. For this purpose the bars 11 which form the structure of the frame are shown as made of angle iron which may be welded, riveted, 60 or otherwise firmly secured at their meeting ends to produce the box-like frame shown in Fig. 2, having open front and rear ends 12, open top and bottom 13 and open sides 14. As constructed, this frame may be moved 65 through the water with great freedom and cause very slight resistance owing to the small area which is in contact with the water.

For the purpose of reciprocating the 70 frame 10, a rod 15 is rigidly connected to one end thereof in any convenient and secure manner. One means for making this connection is shown in the drawings and consists of a sleeve 16 fixed on the end of the 75 rod 15 and having a plurality of radial arms 17 at the base thereof bolted or riveted to diagonal brace bars 18 that cross each other at one end of the frame as clearly shown in Figs. 2 and 3 of the drawings. 80

Within the frame 10 are hinged two 85 swinging blades 19 that are adapted as the propeller is moved in a fore and aft direction to swing open and to close to properly function for forcing through the water the boat upon which the propeller is mounted.

The blades 19 are of a length to extend 90 entirely across the frame 10 and are hinged respectively near one edge in the sides of the frame at the top and bottom thereof, the width of the blades being such that their free edges are substantially together in the center of the frame when in closed operative position. The pivotal axes 20 of the

blades are in vertical alinement so that when 95 the blades close to act on the water they present a substantially unbroken flat surface having a width and height equal to the like dimensions of the frame 10. To limit the movement of the blades 19 when fully open, stops 21 are mounted on the top and bottom frame bars 11, these stops being shown in Fig. 3 in the form of depending spring fingers, while in Fig. 4 inwardly projecting pins are employed. Stop pins 22 may project inwardly from the side bars 11 at the front of the frame 10 for the blades to strike when in closed position. 100

Preferably the hinge pivots 20 project 110 from the side edges of the blades 19 between their meeting and the opposite edges as shown in Figs. 2, 3 and 4; the pivots being

at a greater distance from the meeting edges than from said opposite edges, an arrangement which makes the blades very sensitive to the action of the fluid in which they 5 operate when the thrust is made. It also causes them to abut more quietly against the stops.

In the form of propeller shown in Fig. 3, the swinging blades 19 are hinged at the 10 extreme forward end of the frame 10 and represent the preferred form of propeller which will be mounted at the bow of the boat; for the propeller at the stern of the boat the slight modification shown in Fig. 15 4 is intended to be used. In this form the blades 19 are hinged midway the length of the frame 10 and at the top and bottom of the frame in vertical alinement but swing toward the end of the frame opposite that 20 to which the thrust rod 15 is attached and in this position they move freely through the water. Upon movement of the propeller in the opposite direction or stern-wise, the blades close and stand in alinement as 25 shown in dotted lines in Fig. 4, being maintained in this position by stop pins 23 projecting inwardly from horizontal bars 24 on the side of the frame 10. It will be noted that the stops 21 which limit the opening 30 movement of the blades are nearer to each other than the pivots 20 of the blades themselves. This results in preventing the blades from opening into planes strictly at right angles to the plane they occupy when 35 closed, or in other words when the blades are open they do not stand strictly along the line of progress. As a result, when the propeller is again forced to the rear, the free edges of the blades are caught on the 40 water and the blades are forced closed against the stops 22 or 23.

A propeller such as described may be mounted at the bow or the stern of the boat, or both at the bow and stern, being used 45 singly or in pairs at either or both ends of the boat and when used in pairs they operate alternately. When a boat is provided with a propeller at the bow and another at the stern as in Fig. 1 the thrust rods 15 are 50 mounted to slide horizontally in suitably placed bearings 25, the rods 15 being in alinement and their inner ends terminating adjacent a steam, gas or other motive power engine, not shown. This engine drives a 55 power shaft 26 to which is keyed a crank or crank disk 27, to the crank pin 28 of which are pivoted two connecting rods 29 that extend in opposite directions from said crank pin to the inner ends of the two thrust 60 rods 15 to which they are pivoted as at 30.

In operation, the engine drives the shaft 26 and rotates the crank 27 which through the connecting rods 29 reciprocate the thrust rod 15 and the propellers mounted thereon 65 in a fore-and aft direction. On the for-

ward movement of the propellers, the blades 19 of the forward propeller illustrated in Fig. 3 and the rear propeller shown in Fig. 4, swing to the rear or in open position and lie substantially in line with the direction 70 of movement of the propellers and so offer little or no resistance to the movement of the propeller forwardly. The movement of these blades is caused by the action of the water on their forward faces, but upon reverse movement or movement in a rearward direction the pressure of water against the opposite faces of the blades swings them into closed position against the stops 22 and 23 so that they present at each end of the boat an 80 extensive rigid surface that, pressing against the water, forces the boat in a forward direction. By duplicating the propellers at the bow and stern and operating them alternately, a practically continuous pressure 85 against the water in a rearward direction will operate to force the boat fitted with these propellers in a forward direction and at a rapid rate of speed. If desired, the propeller frame 10 may be equipped with 90 two or more sets of blades 19 as in Fig. 5, the sets being placed one behind the other as shown to operate in unison. In this form, stop pins 31 project inwardly from the frame and serve to limit the open position of one set of blades and the closed position of the blades next in rear. By constructing the frame 10 as shown in skeleton form, no impediment is offered to access of 95 water to the blades of the propeller and so 100 great rapidity of movement is possible and consequently rapid movement of the boat through the water.

A propeller of this type if made of aluminum or some other light strong metal can 105 be mounted on aeroplanes and form the driving means therefor in place of the screw propeller now in common use; the propeller may also be used to submerge or raise boats, pump water, as a ventilator for 110 houses, mines and other places, and wherever the screw propeller is now used the present device may be substituted therefor.

The foregoing description and the drawings have reference to what may be considered the preferred, or approved, form of my invention. It is to be understood that I may make such changes in construction and arrangement and combination of parts, materials, dimensions, et cetera, as may prove 115 expedient and fall within the scope of the appended claims.

Having thus fully described my invention, what I claim as new and desire to secure by Letters Patent, is:

1. A device of the class described comprising a reciprocating rod, a frame comprising a pair of upper horizontally extending and spaced apart bars and a pair of lower horizontally extending and spaced 130

5 apart bars, vertical bars connecting the ends of said horizontal bars, vertical rods connecting the upper horizontally extending bars with their corresponding horizontally extending bars, said vertical rods provided with spaced apart stop pins adjacent their central portions, blades hingedly mounted between said horizontal bars adjacent said vertical bars.

10 2. A device of the class described comprising a reciprocating rod, a box like frame comprising a pair of upper horizontally extending and spaced apart bars, and a pair of lower horizontally extending and spaced 15 apart bars, vertical bars connecting the ends of said horizontal bars, means provided for connecting one end of said reciprocating rod to said frame, blades hingedly mounted within said frame so as to pivot between 20 said horizontal bars, means carried by said frame for stopping said blades when in a closed position.

3. A device of the class described comprising a reciprocating rod, a box like

frame, means for connecting said box like 25 frame to one end of said reciprocating rod, said frame comprising a pair of upper horizontally extending and spaced apart bars, and a pair of lower horizontally extending and spaced apart bars, vertical bars connecting the ends of said horizontal bars, rods 30 connecting the upper bars with their corresponding lower bars, said rods provided with spaced apart stop pins adjacent their central portions, blades pivotally mounted 35 between said horizontally extending bars and adjacent said rods, and abutments provided upon said horizontal bars so that when said blades are in an open position they will converge toward each other, thereby having a tendency to take a closed position when said frame is reciprocated.

40 In testimony whereof I affix my signature in presence of two witnesses.

ROBERT C. PRATT.
